ELECTRICAL SWITCH

Louis Bentzman, Oak Hill, Del., assignor to Saxony Electronics, Inc., Wilmington, Del., a corporation of Delaware

Application September 12, 1956, Serial No. 609,394

2 Claims. (Cl. 200—5)

This invention relates to a switch for controlling the interconnection of electrical circuits, and more particularly to a switch as aforementioned which connects these circuits in various combinations.

Electrical systems frequently include a number of subsidiary circuits which in operation are optionally connected to a source of power and to each other in various combinations. Various electrical appliances, for example electric blankets, include a number of heating elements which are optionally connected in various combinations to provide various rates of heating. A switch for controlling an appliance of this type should have a simple, economical structure which is adaptable for controlling many circuit variations, yet is simple to operate.

An object of this invention is to provide a switch having a structure which is simple and economical to manufacture, which can control the interconnection of a large number of circuits in many combinations, and which is simple to operate.

In accordance with this invention, a number of conductors having tongues projecting at predetermined intervals are assembled with the tongues spaced from each other and aligned in selected groups. A closure means is operatively associated with each aligned group of tongues for selectively moving them into electrical contact. Each conductor is connected to a particular electrical circuit. Movement of each of the closure means interconnects the circuits having tongues in the particular aligned group brought into electrical contact by its movement.

Novel features and advantages of the present invention will become apparent to one skilled in the art from a reading of the following description in conjunction with the accompanying drawings wherein similar reference characters refer to similar parts and in which:

Fig. 1 is an exploded perspective view of electrical components of an embodiment of this invention;

Fig. 2 is a schematic side view in elevation showing alternate operating positions of the assembled electrical components shown in Fig. 1;

Fig. 3 is a front view in elevation of the outside of an assembled embodiment of this invention;

Fig. 4 is a side view in elevation of the embodiment shown in Fig. 3;

Fig. 5 is a cross-sectional view taken through Fig. 3 along the lines 3—3;

Fig. 6 is a cross-sectional view taken through Fig. 3 along the lines 6—6;

Fig. 7 is a cross-sectional view taken through Fig. 3 along the lines 7—7;

Fig. 8 is a plan view of the upper half of the casing of the embodiment shown in Fig. 3;

Fig. 9 is a plan view of the lower half of the casing of the embodiment shown in Fig. 3;

Fig. 10 is a plan view of the lower casing half and various elements of the embodiments shown in Fig. 3;

Fig. 11 is a cross-sectional view in elevation taken through Fig. 4 along the line 11—11;

2

Fig. 12 is a simplified schematic diagram of electrical components and a closure element of the embodiment shown in Fig. 10;

Fig. 13 is a plan view of a closure element of the embodiment shown in Fig. 10;

Fig. 14 is a cross-sectional view taken through Fig. 13 along the line 14—14;

Fig. 15 is a bottom plan view of the closure element shown in Fig. 13;

Fig. 16 is a view in elevation of the closure element shown in Fig. 13;

Fig. 17 is a plan view of an actuating element of the embodiment shown in Fig. 10; and

Fig. 18 is a cross-sectional view taken through Fig. 17 along the line 18—18.

Fig. 1 is an exploded view of a number of conductors 10, 12, 14 and 16, four for example, in the relative positions they assume in the embodiment of this invention described herein. Strips of insulation 18, Micarta for example, are interposed between the conductors to isolate them from each other when they are assembled.

Conductor 10 may be termed a common conductor and it includes a number of tongues 20₁—20₁₅ for example, projecting consecutively at regular intervals along its length. Conductor 12 includes a pair of tongues 22₁ and 22₂, for example, projecting at intervals corresponding to the positions of tongues on conductor 10 having identical subscripts. Conductor 14 has two tongues 24₄ and 24₉ for example, projecting at intervals corresponding to tongues on conductor 10 having identical subscripts; and conductor 16 has three tongues 26₆, 26₁₀ and 26₁₂, for example, projecting at intervals corresponding to the tongues on conductor 10 having identical subscripts.

Conductor 10 is elongated to the right, for example, to form an extension or terminal 30 for connecting conductor 10 to a circuit. Conductors 12, 14 and 16 are elongated in the opposite direction, for example, to provide respective extensions or terminals 32, 34 and 36. When these conductors and interspersed insulating strips 18 are assembled, the various tongues are spaced from each other and aligned in groups corresponding to their subscripts.

Fig. 2 is a schematic side view in elevation of the components shown in Fig. 1 assembled in operative positions. Tongues 20₁ to 20₁₅ are represented by a single tongue designated by reference character 20 and is shown in two phases of operation. The other tongues are also represented in the same manner but in only one position.

The open circuit position of tongue 20 is shown in full outline, and the closed circuit position is shown in broken outline. Indentations 40 are indicated on each of the tongues which provide extended areas of contact when they are brought into electrical contact with each other.

A closure means 42 is indicated in phantom outline in the position it occupies when it is moved in the direction of the arrows to depress a group of tongues 20 of conductor 10 into electrical contact with the tongues of the other conductors which lie under the depressed group of tongues 20. The remote ends 43 of tongues 20 are bent to form a projection which engages an indentation 45 in the lower surface of closure element 42 to lock the tongues 20 in the "make" position. In Fig. 2 the tongues 22, 24 and 26 of lower conductors 12, 14 and 16 respectively are bent upward to a level immediately below the level of the undepressed tongue 20. Movement of tongues 20 connects them directly to each of the lower tongues. Other arrangements, however, may be provided where closure movement of a tongue interconnects a group of spaced tongues to each other. The arrangement herein shown, however, has the advantage of re-

70

quiring minimum movement of the tongue to make contact.

Referring to Figs. 3-11, details of an embodiment of this invention enclosed in a casing described in Figs. 3 and 4 are illustrated. Casing 50, shown in Figs. 3 and 4, may be described as a flattened oblate spheroid having push buttons 52, 54, 56, 58 and 60 projecting from a longitudinal cutout. The flat sides and back side of the casing fit conveniently into a human hand with the push buttons in an extremely convenient position to be actuated by the fingers of the hand which holds the casing. The novel appearance of this particular casing is disclosed and claimed in copending design application S.N. 42,009, filed June 25, 1956. The basic mechanism disclosed and claimed herein is adaptable to many other convenient and decorative forms. The illustrated case, for example, provides the advantage in that it may be conveniently grasped and actuated in accordance with the relative positions of the fingers with respect to the cutout. This switch, accordingly, is very useful for controlling electrical appliances such as an electric blanket in the dark.

Figs. 5, 6 and 7 are cross-sectional views taken through Fig. 3 to show the internal configuration of the switch at various longitudinal sections. Before describing the individual features of these cross-sectional views, the parts shown within the switch are discussed to guide in analyzing the assembled configurations.

Figs. 8 and 9 are respectively the upper and lower halves 64 and 92 of casing 50. The terms upper and lower are merely used for convenience in designation because the switch may be operated in any position.

Fig. 8 shows that the interior of upper casing 64 is hollow and includes various functional projections. A pair of longitudinal strips 66 and 68 provide a surface for confining movement of a closure and cooperating actuating means. Pins 70 project upwardly from strip 68 and provide centering and retaining means in cooperation with a slot 71 in the closure means (later described). Connecting ribs 72 between strips 66 and 58 merely provide structural support.

A pair of posts 74 and 76 project from the interior of casing 64. Holes 78 and 80 respectively in posts 74 and 76 provide anchoring means for screws which pass through a pair of corresponding posts in the lower half 92 to hold the two halves assembled.

Apertures 82 and 84 are provided at the ends of casing half 64 for passing wires into the interior. Ribs 86 and 88 project adjacent the apertures 82 and 84 to cooperate with spaced ribs in the other casing half to provide a labyrinth anchor for the wire. Apertures 90 are notched in the cutout side of casing half 64 for passage of pushbuttons 52-60 through the assembled casing.

In Fig. 9, lower casing half 92 has an interior somewhat resembling that of casing half 64. It includes a pair of longitudinal strips 96 and 98 corresponding in position to aforementioned strips 66 and 68. Strips 96 and 98, accordingly, cooperate with strips 66 and 68 to confine a closure and cooperating actuating means which reciprocate between them. Portions of casing half 92 corresponding to upper half 64 are wire passing apertures 100 and 102, labyrinth wire anchoring ribs 104 and 106, joining posts 108 and 110, including counter sunk holes 112 and 114 respectively for cap screws which screw into holes 78 and 80 of posts 74 and 76, and notches 118 for passage of the pushbuttons are provided in the cutout side of casing half 92.

The remaining internal portion of lower half 92 provides a locating and retaining means for the conductors and insulated strips shown in exploded position in Fig. 1. This retaining means includes a longitudinal groove 120 between strip 96 and the aligned edges of a series of projecting ribs, 122₁ to 122₁₆. Ribs 122₁ to 122₁₆ are regularly spaced, for example, to provide regu-

lar intervals or spaces 124₁ to 124₁₅. These spaces correspond to the subscripts of tongues 20, 22, 24 and 26 of conductors 10, 12, 14 and 16 respectively. The elongated portions of conductors 10, 12, 14 and 16 lie in spaces 120 with tongues projecting through respective spaces between ribs 122.

Fig. 10 shows lower casing half 92 with closure means 132, 134, 136, 138 and 140 installed in respective slots or channels between each third rib 122 which are accordingly raised above the intermediate ribs. These raised ribs also isolate the various contacts from each other and may be utilized to prevent arcing over. Pins 70 are shown projecting through slots 71 of the closure elements. Angular actuating elements 142 are restrained in longitudinal groove 97 between strips 96 and 98. These actuators have angular surfaces corresponding to the angular front ends of closure elements 132-140 and provide only enough space therebetween for simultaneous depression of a single pushbutton. Closure element 136 is shown in the depressed condition between a pair of actuating elements 142 which wedge all other closure elements to the undepressed position. When another pushbutton is depressed, any previously depressed closure element returns to the open circuit position. One pushbutton and corresponding closure element provide an open circuit position because of the absence of tongues on contacts 12, 14 and 16 lying beneath it.

Fig. 11 is a longitudinal cross-sectional view in elevation showing casing halves 64 and 92 assembled by means of screws 144. The relative positions of the conductors 10, 12, 14 and 16 and interspersed insulating strips 18, are clearly shown as well as the positions of closure elements 132-140 guided between the raised ribs 122₁, 122₄, 122₇, 122₁₀, 122₁₃ and 122₁₆. Closure elements 132-140 are also guided by pins 70 projecting from upper casing half 64 through slots 71.

Fig. 12 is an enlarged simplified schematic diagram in front elevation of conductors 10, 12, 14 and 16 and interspersed insulating strips 18, showing the relative positions of the various tongues and how they are aligned in groups within channels defined by every third raised rib 122. The tongues are shown in a straight form not corresponding to the actual configuration to more clearly illustrate their relative positions and how movement of a single closure element depresses all tongues 20 of conductor 10 which lie under it to move them into electrical contact with all of the corresponding tongues of other conductors. As shown in Fig. 12, closure element 136 has been actuated to move tongues 20₇, 20₈ and 20₉ downward so that tongues 20₇ and 20₉ move into contact with tongues 22₇ and 24₉ of conductors 12 and 14 respectively. Conductors 10, 12 and 14 are accordingly interconnected. Movement of a closure element may interconnect more than one tongue of two conductors when a higher current carrying capacity is desired, as is provided by closure element 134 which interconnects tongues 20₁₀ and 20₁₂ with tongues 24₁₀ and 24₁₂.

Figs. 13-16 show details of a closure element which is closure element 136, for example. Element 136 roughly includes three functional portions. These portions are pushbutton element 56, angular shifting portion 148 for engaging actuating elements 142, and tongue-operating step 150. The upper portion of the element is hollowed at 152 to conserve material and lighten the element. Slot 71 is provided as previously described for cooperating with pins 70. Step 150 is positioned below lower flat surface 154 which cooperates with flat top surface 156 to ride between the confining surfaces provided by strips 66 and 68 of the upper casing half, and 96 and 98 of the lower casing half. The lower step 150, as shown in Figs. 2, 6 and 7, optionally engages a tongue 20 of conductor 10 to make and break electrical contact with corresponding tongues of strips 12-16. Step 150 includes an indentation 45 for engaging a corresponding projection 43 of a tongue 20 to maintain

tongue 20 and a pushbutton locked in the "make" position. Fig. 6 shows a closure element 136 for example, in the break position with tongue 20 raised out of contact with corresponding tongues. Fig. 7 shows element 136 depressed into the make position with tongue 20 depressed into electrical contact with corresponding tongues of conductors 12-14. The make and break positions correspond to the alternate positions shown in Fig. 2.

Figs. 17 and 18 show details of an actuating or shifting element 142 which includes an angular portion 160 for engaging corresponding angular portions of the closure elements. Element 142 also includes a lug 162 projecting from its lower surface for restraining motion of actuating element 142 in the groove 97 between strips 96 and 98. Upper surface 164 and lower surface 166 of element 142 ride between strips 66 and 68 of casing half 64 and strips 96 and 98 of casing half 92 respectively when these halves are assembled as indicated in Fig. 11. When the switch is assembled, surfaces 164 and 166 of actuating element 142 are substantially parallel to surfaces 154 and 156 of closure elements 132-140.

Operation

Depression of any one of pushbuttons 52-60 moves corresponding actuating elements 132-140 and depresses tongues 20 of conductor 10 which lie beneath the operated closure element. When closure element 136 is depressed, for example as shown in Fig. 12, tongues 20₇-20₉ are brought into electrical contact with tongues 22₇ and 24₉. This interconnects the electrical circuits connected to conductors 10, 12 and 14. Conductor 10 is, accordingly, connected with any combination of three other conductors in accordance with the presence or absence of tongues under a particular closure element. A complete absence of tongues on conductors 12, 14 and 16 under a particular closure element provides an "off" or open circuit condition. The number of possible combinations may be increased further by providing a larger closure element which contacts a greater number of tongues. Addition of conductors may be provided for interconnecting additional electrical circuits.

What is claimed is:

1. An electrical switch comprising an elongated casing whose outer surface is constructed and arranged in a shape which can be conveniently grasped by a human hand, an array of conductors disposed in parallel planes within said casing and having tongues projecting at predetermined intervals, retaining means mounting said conductors within said casing in fixed relationship to each

other with said tongues of said conductors spaced from each other and aligned in predetermined groups, pushbutton closure means operatively associated with said tongues and passing through said casing for selectively moving said tongues within each of said groups into electrical contact with each other, said casing including divider means providing a row of slots, said conductors being elongated and having said tongues disposed at longitudinal positions corresponding to predetermined slots, said tongues being inserted within corresponding slots, predetermined divider means being extended to provide boundaries for predetermined groups of said slots, reciprocating closure elements being inserted between said extended divider means for selectively moving the tongues within said predetermined groups into electrical contact with each other, said pushbutton closure means being disposed in a row along said casing, insulating strips being interspersed between said conductors, said retaining means maintaining said conductors and said interspersed strips in intimate contact with said casing and with each other, said closure elements including projections for depressing predetermined tongues of one of said conductors into electrical contact with corresponding tongues of the others of said conductors, said closure elements including indentations for engaging said predetermined tongues of one of said conductors, and said indentations and tongues being cooperatively formed to maintain said closure elements and said tongues locked in the "make" position.

2. An electrical switch as set forth in claim 1 wherein said casing is cut out to provide slotted guide means, shift elements are inserted to slide within said slotted guide means and in contact with said closure elements, the contacting surfaces of said shift elements and said closure elements being cooperatively angularly shaped to react with each other for allowing only one of said closure elements to be operated at one time, and one of said closure elements being available to provide an open circuit.
